SHEET-FEEDING MACHINE.

1,072,937.

Specification of Letters Patent.

Patented Sept. 9, 1913.

Application filed April 20, 1908. Serial No. 428,259.

To all whom it may concern:

Be it known that I, RUFUS A. FREEMAN, a citizen of the United States, and a resident of Flushing, Queens county, State of New York, have invented certain new and useful Improvements in Sheet-Feeding Machines, of which the following is a specification.

The invention relates to sheet-feeding machines and more especially to sheet-feeding machines which feed off sheets from the face of a stack, the stack-supporting table being raised as the sheets are fed off to keep the face of the stack in operative relation with the feeding-off devices.

Objects of the invention are to provide a mechanism which is very sensitive to variations in the relation of the stack to the feeding-off devices, and which will reduce such variations to a minimum; which is capable of raising the table by very small increments; which is direct and reliable in action; which is simple and strong in construction, and which is well adapted for high-speed feeding. These and other objects of invention will in part be obvious and will in part be more fully set forth herein.

The invention consists in the novel parts, combinations, arrangements and improvements herein shown and described.

The accompanying drawing, representing a side elevation of a machine constructed in part in accordance with the principles of the invention, constitutes a part hereof and serves herewith to illustrate the principles of the invention.

The success and efficiency of a sheet-feeding machine depend largely upon maintaining a constant relation between the face of the sheet stack and the feeding-off devices and the maintenance of such a relation depends to a great extent upon efficient table-raising mechanism. By maintaining such a constant relation, the feeding of a plurality of sheets, failure to feed a sheet, irregularity in feeding off the sheets, and other objections are avoided, even when sheets are fed off at high speeds.

In the accompanying drawing there is shown a stack 1 of sheets carried by a suitable table 2. Suitable devices for feeding off sheets from the face of said stack will be used but not illustrated herein. Such devices may be employed similar to those dis-

closed in my co-pending application for patent Serial Number 395,388 filed October 1, 1907. Suitable supporting devices for said table are provided and also devices co-acting therewith to feed the table upwardly in such manner as to maintain as nearly as possible a uniform relation between the face of the stack and the feeding-off devices. In the present embodiment the supporting and feeding-up devices for the table are shown as comprising sprocket chains 3 located substantially centrally of the table upon either side thereof. Said chains are shown passing over suitable sprocket wheels 4, mounted on the frame 5, and also over suitable sprocket wheels 6 carried upon a shaft 7 mounted in the lower part of the frame 5. Said chains are attached to the table 2 in a suitable manner, as at 8. Fixed also upon the shaft 7 are shown sprocket wheels 9 carrying sprocket chains 10 which likewise pass over sprocket wheels 11. Suitable devices for moving the hereinbefore described mechanism are provided including a ratchet wheel 12 shown connected by suitable gears 13 and 14 to the sprockets 4 and 11. For the purpose of rotating the ratchet wheel 12 there is shown a pawl 15 pivoted on a reciprocable rod 16. Said rod is shown mounted to reciprocate longitudinally and suitable means for so reciprocating it are provided. In this embodiment a suitable cam 17 is shown arranged to positively advance said rod to feed up the table. In the drawings the rod 16 is shown mounted to slide in a lug 18 upon the frame of the machine and having a slotted connection with the shaft 19 of the cam 17. A suitable anti-friction roll 20 is shown mounted upon the rod for the purpose of bearing upon the cam 17. Means are provided which act to retract said rod after it has been advanced to feed up the table. As shown in the present embodiment, a spring 21 tends to hold the rod 16 to its cam and thus acts to retract the rod with the movement of the cam. Said spring is conveniently shown herein under compression between the lug 18 and an adjustable collar 22 carried upon the rod 16. For the purpose of allowing or preventing the reciprocation of said rod, suitable means are provided. As shown herein, such means act to control the action of the spring 21 upon the rod 16. A movable dog 23 is shown of angular form and

suitably pivoted upon the frame of the machine at 24. Said dog is constructed and arranged to move into and out of engaging position with respect to a lug 25 upon the 5 rod 16, thus either preventing or allowing the rod, acting under impulsion of the spring, to follow its cam. It will be seen also that but a very slight variation in the movement of the dog is necessary to either 10 allow or prevent the reciprocation of the rod as the case may be.

Acting upon the face of the sheet stack is shown a suitable feeler 26 which is further shown as being vertically slidable in a suitable support 27. There are also provided motion multiplying connections between the feeler and dog for moving the dog. In this embodiment said connections comprise a member connected directly to said feeler 26 15 and dog 23 to cause the feeler to move the dog and thus control the action of the pawl 15 upon the ratchet wheel 12. Said member is shown as comprising an arm 28 engaging the feeler 26 and fixed upon a shaft 29, and 20 having an arm 30 likewise fixed to said shaft and connected to the dog 23 at a distance from the pivot of the latter which is short 25 as compared with the length of the arm 30, whereby the motion of the dog is multiplied 30 with relation to that of the feeler. According to one feature of the invention means are provided for readily varying the relation between the feeler and the dog to enable the height of the sheet stack to be nicely regulated 35 with relation to the feeding-off devices. Preferably this is accomplished by threading the grooved collar 28^a which is engaged by the arm 28, and screwing it on a correspondingly threaded stem 26^a of the feeler, 40 the collar being held in its adjusted position by a suitable jam-nut. By means of this construction the relation between the stack and the feeding mechanism may be varied without stopping the machine.

45 It will be understood that as the sheets are fed off from the top of the stack the feeler 26 descends until the engaging end of the dog 23 is moved out of the path of the lug 25 and then the spring 21 will act to cause 50 the rod 16 to reciprocate with the rotation of its cam 17, carrying the pawl 15 backward over the toothed ratchet wheel 12 and as the cam moves the rod in the opposite direction, the ratchet wheel 12 will be rotated 55 to give a feeding-up movement to the table and sheet stack. On the other hand, when the table has been fed up a very little, the feeler 26 will descend a less distance and the lever arms 28 and 30 will not be rocked 60 sufficiently to lift the engaging end of the dog 23 out of the path of the lug 25. As but a very slight motion of the dog 23 in one direction or the other will either arrest the rod or permit it to pass, as has been noted 65 above, it will be seen that the mechanism is

one of great sensitiveness and may be arranged to cause a feed of a single tooth of the ratchet wheel 12. As this wheel may be of considerable size, it will be seen that the mechanism, as stated, is not only sensitive in detecting small variations in the height of the stack, but it will give a frequent and small feed thus maintaining very nearly absolute predetermined conditions between the feeding-off devices and the face of the stack. 70 It will further be seen that said devices are characterized by great strength and simplicity.

Suitable devices are provided for lifting the feeler out of pressure contact with the 80 face of the stack during the feeding-off of successive sheets, and in the present embodiment said means are shown acting directly upon the lever 28-30. The illustrated form thereof comprises a link 31 connected to the 85 arm 30 and, by a pin-and-slot connection to an arm 32 which is actuated by a suitable cam 33. Said arm serves also to actuate the drop rollers 34 carried upon arms 35. It will thus be seen that said devices serve to 90 relieve the pressure contact of the feeler upon the face of the stack as the sheets are being fed off.

A suitable check pawl 36 is shown for preventing backward movement of the ratchet 95 wheel 12. A handle 37 is also shown upon said ratchet wheel, so that same can be rotated by hand. This permits rapid movement of the table in either direction as by throwing out the pawl 36 the table may be 100 moved in either direction.

The opening of the mechanism will be clearly understood from the foregoing description. It will be also understood that a machine has been provided which realizes 105 the objects of invention and the advantages herein set forth together with other objects and advantages.

It will be understood that changes may be made in the mechanism shown and described 11 without departing from the principles of the invention and without sacrificing its advantages.

I claim:—

1. A sheet-feeding machine including in 11 combination, a table for supporting a sheet stack, a pawl and ratchet mechanism for raising the table, said pawl and ratchet being located near the top of the sheet stack, a reciprocating member for actuating the 12 pawl, means for positively advancing said reciprocating member to feed up the table, means acting to retract said reciprocating member, a dog for preventing said retracting means from acting, a feeler acting on the face of said sheet stack, a rock shaft connected to said feeler, and a relatively long arm on said rock shaft directly engaging a relatively short arm on said dog.

2. A sheet-feeding machine including in 13

- combination, a table for supporting a sheet stack, a pawl and ratchet mechanism for raising the table, said pawl and ratchet being located near the top of the sheet stack, 5 a reciprocating member for actuating the pawl, means for positively advancing said reciprocating member to feed up the table, means acting to retract said reciprocating member, a dog for preventing said retracting means from acting, a feeler acting on the face of said sheet stack, a rock shaft connected to said feeler, a relatively long arm on said rock shaft directly engaging a relatively short arm on said dog, and means acting 10 directly on said feeler-actuated arm for intermittently lifting the feeler out of pressure contact with the face of the stack.
3. A sheet-feeding machine including in combination, a table for supporting a sheet stack, table raising means including a ratchet wheel located near the top of the stack, a handle on said wheel for quickly moving the stack, a reciprocable rod having a pawl pivoted directly thereon for engaging 15 said ratchet wheel, means for reciprocating said rod, a movable dog for allowing or preventing the reciprocation of said rod, a feeler acting on the face of the sheet stack, and connections between said feeler and dog 20 for moving the rod engaging portion of the dog with a motion which is many times greater than that of the feeler.
4. A sheet-feeding machine including in combination, a table for supporting a sheet stack, table raising means including a ratchet wheel located near the top of the stack, a longitudinally reciprocable rod having a pawl pivoted directly thereon for engaging said ratchet wheel, means for positively advancing said reciprocating rod to feed up the table, a dog for preventing said reciprocating means from acting, a feeler acting on the face of the sheet stack, a rock shaft connected to said feeler, and a relatively long arm on said rock shaft directly engaging a relatively short arm on the dog to cause the feeler to move the dog positively 25 with a greatly multiplied motion.
5. A sheet-feeding machine including in combination, a table for supporting a sheet stack, table raising means including a ratchet wheel, a rod reciprocable longitudinally and having a pawl pivoted directly thereon for engaging said ratchet wheel, a cam for reciprocating said rod, a spring for holding said rod to its cam, a movable dog 30 for controlling the action of said spring on the rod, a feeler acting on the face of the sheet stack, and a rock shaft having an arm connected to the feeler and a relatively long arm connected to a relatively short arm on the dog. 35
6. A sheet-feeding machine including in combination, a table for supporting a sheet stack, a chain for supporting said table, a shaft at the bottom part of the machine connected to said chain, mechanism including a ratchet wheel near the top of the machine also connected to said chain, a pawl for moving said ratchet wheel, a dog for controlling 40 said pawl, a feeler acting on the face of the sheet stack, motion-multiplying connections between said feeler and said dog, and a handle on said ratchet wheel for actuating the table by hand. 45
7. A sheet-feeding machine including in combination, a table for supporting a sheet stack, a shaft near the bottom of the machine, a ratchet wheel near the top of the machine, connections between said ratchet 50 wheel, shaft and table, a reciprocable rod having a pawl pivoted thereon for engaging said ratchet wheel, a cam for reciprocating said rod, a movable dog for allowing or preventing the reciprocation of said rod, a feeler acting on the face of the sheet stack, motion-multiplying connections between said 55 feeler and dog to cause the feeler to move the dog, a handle on said ratchet wheel, and a check pawl for said ratchet wheel. 60
8. A sheet-feeding machine including in combination, a table for supporting a sheet stack, table-raising means including a ratchet wheel, a reciprocating rod having a pawl pivoted directly thereon for engaging 65 said ratchet wheel, means for reciprocating said rod, a movable dog for allowing or preventing the reciprocation of said rod, a feeler acting on the face of the sheet stack, motion-multiplying connections between the feeler and dog for moving the dog, and means for readily varying the relation between the feeler and the dog, whereby the portion of the top of the stack may be varied without 70 stopping the machine. 75
- In testimony whereof, I have signed my name to this specification, in the presence of two subscribing witnesses.
- RUFUS A. FREEMAN.

Correction in Letters Patent No. 1,072,937.

It is hereby certified that in Letters Patent No. 1,072,937, granted September 9, 1913, upon the application of Rufus A. Freeman, of Flushing, New York, for an improvement in "Sheet-Feeding Machines," an error appears in the printed specification requiring correction as follows: Page 3, line 103, for the word "portion" read *position*; and that the said Letters Patent should be read with this correction therein that the same may conform to the record of the case in the Patent Office

Signed and sealed this 18th day of November, A. D., 1913.

[SEAL.]

R. T. FRAZIER,
Acting Commissioner of Patents
